UNITED STATES PATENT OFFICE.

DAVID STRAITON, OF AKRON, OHIO, ASSIGNOR TO THE MILLER RUBBER COMPANY,
OF AKRON, OHIO, A CORPORATION OF OHIO.

DESIGN FOR A DOLL.

Application filed December 26, 1922. Serial No. 4,711. Term of patent 14 years.

To all whom it may concern:

Be it known that I, DAVID STRAITON, a citizen of the United States, and resident of Akron in the county of Summit and State of Ohio, have invented a new, original, and ornamental Design for a Doll, of which the following is a specification, reference being had to the accompanying drawing, forming part thereof.

In this drawing:

The figure is a front view of the doll in elevation.

I claim:

The ornamental design for a doll, as shown.

DAVID STRAITON.
